(57) **CLAIM**

I claim the ornamental design for a notebook computer, as shown and described.

DESCRIPTION

FIG. 1 is a front perspective view of a notebook computer showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another perspective view thereof;

FIG. 9 is a bottom perspective view thereof; and

FIG. 10 is an enlarged view of the encircled portion '10' in FIG. 1;

FIG. 11 is an enlarged view of the encircled portion '11' in FIG. 2;

FIG. 12 is an enlarged view of the encircled portion '12' in FIG. 5; and,

FIG. 13 is an enlarged view of the encircled portion '13' in FIG. 9.

The even-dash broken lines in the figures depict portions of the notebook computer which form no part of the claimed design.

The dot-dash lines adjacent to claimed surfaces represent boundaries of the claimed design and form no part thereof. The dot-dot-dash broken lines encircling portions of the design in FIGS. 1-2, 5 and 9-13 represent the extents of the detail views and form no part thereof.
